DOOR CHECK AND HOLDER

Richard H. Wright, Cleveland, Ohio

Application November 6, 1936, Serial No. 109,573

2 Claims. (Cl. 16—86)

This invention relates to door checks which are primarily intended for use with doors of automobiles or other vehicle bodies, and the like. More particularly, the invention has to do with 5 an improved door check structure wherein means is provided for maintaining the door in one or more predetermined positions, more especially, an open position.

In door check devices heretofore in use for automobile doors, it has been suggested to provide 10 an arm or shank which is pivotally secured to the hinge edge of the door or the hinge post of the vehicle body, the opposite end of the arm or shank extending through the contiguous edge 15 of the hinge post or the door, as the case may be, and having mounted thereon a resilient buffer member adapted to cushion the opening movement of the door and yieldably check the same. However, as far as I am aware, no provision 20 has been made in any practical door check structure of the types heretofore employed, for preventing the door from immediately swinging closed by its own weight or by the rebounding of the door resulting from the cushioned checking 25 of the same at the end of its opening movement.

It is an object of the present invention to provide a simple and inexpensive door check, together with an equally simple and inexpensive 30 spring stop adapted to cooperate with the door check in such manner that the door will be held open automatically when swung to its fully opened position, while allowing the door to be released readily for closing the same and without departing from the normal manner of opening and closing the door.

A still further object of the invention is to provide an improved door check structure wherein 40 the door will be more or less frictionally held in any position so as to normally prevent the door from swinging one way or the other by its own weight or by an inadvertent jarring of the same.

More specifically, the invention is characterized by the provision of a door check arm or shank, one end of which is adapted to be pivotally mounted on a suitable support, and the 45 opposite end of which has mounted thereon a suitable yieldable buffer adapted to cooperate with an abutment on the door, together with a spring member which is so mounted with relation to the door check arm as to cause the spring member to releasably interengage with the buffer means when the latter engages the abutment 50 aforesaid.

Other objects and advantages of the invention will be hereinafter described, and the novel features thereof defined by the appended claims.

In the drawing:—

Figure 1 is a fragmentary horizontal sectional view, taken on a plane through a door and body structure of a motor vehicle or the like, substantially at the point of attachment of the door check, the door check being shown partly in section and partly in elevation, and embodying 5 the improved spring stop feature which forms a part of the invention, the parts being shown in their relative positions when the door is closed;

Figure 2 is a view generally similar to Figure 15 1, illustrating the relative positions of the parts when the door is open, and showing the action of the spring stop member in releasably holding the door in open position;

Figure 3 is a fragmentary detail view in side 20 elevation of the door check parts and the spring stop in their engaged positions; and

Figure 4 is a detail view of the parts illustrated in Figure 3, as seen in end elevation.

Like reference characters designate corresponding parts in the several figures of the drawing, wherein 1 designates a door hingedly mounted upon a vehicle body, generally designated 2, by means of suitable hinges 3. These parts may be of conventional design, and it is 30 to be understood that while reference is made herein to doors of motor vehicle bodies and the like, the invention is not limited to this field, and such doors have been illustrated and described merely by way of illustration of one 35 application of the invention. The number of hinges 3 by means of which the door is mounted on the body structure is immaterial.

Pivotedly mounted, as at 4, through means of a bracket 4' secured to the hinge edge 5 of 40 the door, is a door check arm or shank 6, which may be made of relatively flat bar material of preferably less thickness than width. This arm or bar extends away from the hinge edge of the door and through a suitable opening 7 provided 45 therefor in the contiguous edge 8 of the body structure 2. For convenience, this edge 8 may be termed the hinge post of the body. The free end 9 of the bar or arm 6 is bent laterally so as to permit the check arm to slide through the opening 7 as the door is swung open and closed and so that when the door is closed, the check arm 6 will lie within the usual space afforded between the inner and outer walls of 50 the vehicle body 2. The extent of curvature of 55

- the part 9, and the general shape of the arm may be varied to accommodate different types of door and body structures, and while the check arm has been shown as operating in a more or less horizontal position, it might also be used to operate in a more or less vertical position as in the case of application to doors or swinging parts which are adapted to swing about a horizontal axis.
- 5 10 Mounted on the free end 9 of the check arm 6 is a resilient buffer member 10, preferably composed of rubber or other yieldable material, the same being provided with an opening therethrough so that the buffer member may be slipped on over the end of the check arm, the opening through the buffer having a tight fit on the arm. The purpose of this buffer 10 is to limit or check the opening movement of the door 1 and absorb the shock incident to such 15 checking of the door movement as it approaches the limit of its fully open position. The buffer member 10 is retained on the arm 6 by a retainer disc or washer 11, which, when assembled on the free end 9 of the arm 6, is preferably positively interlocked therewith through interengagement of the disc with notches or recesses 12, 12 20 in the opposite edges of the arm adjacent to the free extremity thereof. As a convenient means of interlocking the disc 11 with the notches 12, 12, the disc is provided with a recess 13 extending from its periphery to about the center, and before the disc is mounted on the arm 6, the opposite walls 14, 14 of the recess 13 are preferably normally parallel and spaced apart 25 sufficiently so that the portion of the arm intermediate the recesses 12, 12 may be freely passed into the recess 13 of the disc 11 until the arm 6 is approximately centered with respect to the disc. Thereupon, the recess 13 is constricted or 30 closed, as by pressing or forcing the portions of the disc at opposite sides of the recess towards each other through means of any suitable instrumentality. In thus constricting or closing the recess 13, as best seen in Figure 4, the retainer disc or washer 11 becomes positively and 35 rigidly interlocked with the arm, and there is no possibility of the same becoming inadvertently displaced during use of the door check. Moreover, such a construction has no tendency to develop rattles by reason of any likelihood of the 40 parts becoming loosened during use.
- 45 Passing now to the description of the spring stop by means of which the door may be held in an open position, I mount on the inside of the hinge post 8 of the body 2, within the usual space afforded between the inner and outer walls of the body structure, a pair of spaced spring arms or fingers 15, 15 located respectively at opposite sides of the opening 7, there being sufficient space afforded between these arms or fingers 15, 15 to allow the check arm 6 to freely move therebetween during the opening and closing movements of the door. Normally, however, the space between the arms 15, 15 is slightly less 50 than the diameter or width of the buffer member 10, so that when the door is fully opened to the position illustrated in Figure 2, the buffer member 10 will be drawn between the arms 15, 15 and will be frictionally engaged thereby with a substantial clamping pressure. To still further increase the effectiveness of the arms 15, 15 in holding the door in its open position, I preferably provide a recess 16 in each of the arms 15, 55 these recesses being suitably formed as by bending the material of the arms 15, 15 as best seen

in Figures 1 and 2, at a point where the opposite marginal edges of the retainer plate or disc 11 will be received in said recesses, as shown in Figure 2, when the door is swung open to the limit of its movement. The free end 17 of each of the fingers or arms 15 is offset or inclined laterally so that together, these portions 17 facilitate the entrance of the buffer head assembly composed of the buffer 10 and the retainer 11, therebetween, and serve to guide the check arm 6 10 as it approaches the end of its movement during the opening of the door.

15 By extending the base 18 of each arm or finger 15 towards each other sufficiently far to closely engage the opposite edges of the check arm 6 with a firm frictional engagement, the guiding of the arm 6 is further facilitated. This frictional engagement just mentioned may also be utilized to check the movement of the door and temporarily hold the door in any position 20 intermediate the extreme open and closed positions. As best seen in Figures 1 and 2, the arms or fingers 15, 15 are preferably mounted on the hinge post 8 of the body 2 in slightly spaced relation to the latter, this spacing being 25 maintained by one or more spacing plates 19 which serves to reinforce the hinge post at the opening 7, the spacing plate, of course, being provided with a suitable opening aligned with the opening 7 to allow the check arm 6 to extend therethrough.

30 Since the retainer 11 is preferably circular in form, I prefer to curve the arms 15 transversely, as best seen in Figure 4, so that these fingers will closely embrace the retainer when it is 35 drawn therebetween according to the manner of Figure 2.

35 The operation of the invention should be readily apparent from the foregoing, and may be briefly summarized as follows: Assuming the 40 door 1 is closed as shown in Figure 1, upon opening of the same to the position shown in Figure 2, the check arm 6 will slide through the aperture 7 in the hinge post of the body 2 until the buffer 10 abuts the inner faces of the bases 45 18 of the oppositely disposed arms or fingers 15, 15. Of course, as the buffer 10 enters between the arms 15, 15, the opening movement of the door will be partially checked, leaving only the final impact shock of the buffer 10 against the 50 bases 18 to be absorbed by the resilient buffer. When the parts assume the positions illustrated in Figure 2, the fingers 15, 15, exert a yieldable clamping action upon the buffer 10, tending to at least partially prevent the door from rebounding closed, and this is further augmented by the receiving of the opposite sides of the retainer 11 within the recesses 16, 16 of the fingers 15, 15. In practice, it is desirable to open the door with a slow movement so that there is no 55 great tendency for the same to rebound closed, and in the absence of any excessive force on the door, the door will be positively and firmly held in its open position by the action of the yieldable stop fingers 15, 15. As previously mentioned, the extension of the bases 18 of the fingers 15 into close frictional engagement with the check arm 6 may be utilized as a further check and friction limit stop, especially for intermediate positions of the door as well as for 60 facilitating the guiding of the check arm during its sliding movements through the opening 7.

65 Upon closing the door, the application of a slight force in the direction of closing movement 70

will shift the check arm 6 inwardly through opening 7, thereby retracting the buffer 10 and retainer 11 from between the stop fingers 15, the parts occupying substantially the positions illustrated in Figure 1 when the door reaches its fully closed position.

It is to be understood that in mounting the door check, it may be located anywhere between the upper and lower extremities of the door, as desired. In practice, one check unit per door will generally be found sufficient, although more than one check unit can be provided if this is desirable. It will likewise be obvious that the door check may be mounted in the reverse order from that herein described; that is to say, the check arm 6 may be pivotally mounted on the hinge post of the body 2, rather than the hinge edge of the door 1, in which event, the resilient stop fingers 15, 15 would be mounted on the inside of the hinge edge of the door for cooperation with the buffer assembly which would be accordingly located within the door structure instead of within the body structure, the hinge edge of the door being, of course, suitably provided with an opening for slidably receiving the check arm 6 therethrough. Instead of separately illustrating this reverse order of mounting, the same can be readily understood by considering the part designated 1 as the body structure, and the part designated 2 as the door structure.

While the specific details of construction have been herein shown and described, the invention is not confined thereto, as changes and alterations may be made without departing from the spirit thereof as defined by the appended claims.

Having thus described by invention, what I claim as new and desire to secure by Letters Patent is—

40 1. In a device of the class described, the combination with a door check comprising a check

arm, one end of which is adapted to be attached to the hinge edge of a door, and the check arm being also adapted to extend through the hinge post of the structure upon which the door is mounted, a resilient buffer mounted upon the free end of said check arm, and a retainer member interlockingly mounted upon the free end of said check arm, of a resilient stop member adapted to be mounted upon the hinge post aforesaid for engaging the buffer member when the door is swung to an open position and serving to releasably hold the door in such an open position, said resilient stop member having provision for interengaging with the retainer member whereby to temporarily restrain the door from moving.

2. In a device of the class described, the combination with a door check comprising a check arm, one end of which is adapted to be pivotally attached to the hinge edge of a door, and the check arm being also adapted to extend through the hinge post of the structure upon which the door is mounted, a resilient buffer mounted upon the free end of said check arm, and a retainer disc interlockingly mounted upon the free end 25 of said check arm and having its marginal edges extending laterally beyond the buffer member, of a resilient stop member adapted to be mounted upon the hinge post aforesaid, said resilient stop member comprising spaced spring fingers one at 30 each side of said check arm, between which the buffer member and retainer disc are adapted to be received when the door is opened to the limit of its movement as determined by the buffer member, and when in such open position, said 35 fingers engaging the buffer member with a firm clamping action, and being further provided with recesses receiving the marginal edges of the retainer disc at opposite sides thereof whereby to temporarily restrain the door from moving.

40 RICHARD H. WRIGHT.
